COMPUTING MACHINE

James L. Hutton, Greensboro, N. C.

Application March 1, 1947, Serial No. 731,799

9 Claims. (Cl. 235—60.27)

1

This invention relates to computing and recording machines, and its principal object is to provide a compact, simply constructed machine of comparatively few parts which is easy to operate, is light in weight, economical to manufacture and which can perform a variety of computing functions. To accomplish these and other objects, the machine is designed so that many of the parts can be stamped out of sheet metal, with very few parts requiring the precision tolerances in manufacture heretofore required. The machine is adapted for either stylus or keyboard operation.

Stylus operated adding machines are known, but in these machines of the prior art the stylus must be used to engage and move manually a rack or belt to actuate the registering or printing mechanism. In the present invention, no movement of the stylus is required other than to insert it into the desired digit opening in the stylus board and depress it lightly. This action releases the selector for immediate movement to differential position corresponding to the digit selected.

A further object of the invention is the provision of a loaded differential actuator or automatic selector which is released by stylus or key operation without the necessity of an operating bar to set it in motion. In known machines of the keyboard type, for example, depressing the selected key does not set the selector in motion. An operating handle must be actuated to release the selectors. In this machine, the selectors are automatically released for movement by the stylus or key operation, thus lightening the work load of the operating bar and lessening operator fatigue.

Another object is the provision of a simple and effective mechanism for accomplishing repeat addition, multiplication or division, working in conjunction with the selectors, the parts thereof being few and simple, this mechanism being shown in several forms.

Still another object is the provision of a simple feedback mechanism by means of which any number or total registered in the accumulators may be transferred back to the selectors without manual manipulation of the stylus board or keyboard. This comprises a novel cam and lever arrangement which is simple in construction and very effective in operation, saving much of the operator's time in calculating.

A further object of the invention is the provision in one form of the invention of a shifting carriage for use in multiplication or division,

2

which is located in and shifts entirely within the housing of the machine. A further feature of this carriage is that it is located directly below the selectors and functions without interfering with their operation.

Still a further object is the association in one form of the invention of the shifting mechanism with the feedback and printing mechanisms. A novel feature of this arrangement is that the printing mechanism may be shifted to take a total at any point along the keyboard of the machine. Also, with this mechanism, an operator may feed back any amount or total from the accumulator dials to the selectors and then shift the mechanism to print the same at any point along the keyboard. Thus, one or more columns of figures may be printed without the necessity of shifting the form on which the printing is being done. Each column may represent the same amounts as is necessary for duplicate work, either column may be an accumulative total, or one column may represent individual items and the other an accumulative total. This mechanism therefore will permit duplex work to be done on a single row of dials, the number of dials being determined by the required capacity of the machine.

In one form of the invention the printing mechanism comprises a segment which is actuated by the repeat mechanism operated by the selector, and during repeat operations the segment may be locked in position to print the selected digit, thus lightening the load on the operating bar and speeding up its operation. This construction also eliminates the possibility of an overprint or underprint which might result from swift repeat movement of the operating bar.

Other objects reside in the novel constructions, combinations and arrangements of parts herein described and shown in the accompanying drawings which are illustrative of practical embodiments of the invention and in which

Figure 1 is a perspective view of the machine.

Figure 16 is a side elevational view of a modified form of the repeating and feedback mechanism associated with a novel keyboard construction.

Figure 17 is a front elevational view of the mechanism shown in Figure 16, taken on the line 17—17, looking in the direction of the arrows.

Figure 18 is a plan view of the mechanism shown in Figure 16, taken along the line 18—18, looking in the direction of the arrows.

Figure 19 is a perspective view of a detail similar to Figure 16, but showing a modification having one unit combination in one denomination of a selector with the repeating device and incorporating a printing mechanism set in motion by the actuation of a key on the keyboard.

Figure 20 is a perspective view of a detail of the shifting mechanism supporting means and part of the shifting mechanism, showing the novel printing mechanism combined therewith.

The machine comprises several component mechanisms which for facility of description are outlined as follows:

1. The stylus board and depressor bar.
2. The dial accumulators or registers and the carrying mechanism.
3. Restoring and resetting mechanism.
4. Addition mechanism.
5. The subtraction mechanism.
6. Totalling and clearing mechanism.
7. Correction mechanism.
8. Printing.

9. Stylus or keyboard check dials.

10. The repeat addition or feedback mechanism.

11. Shifting mechanism.

12. Substitute keyboard mechanism.

These mechanism will be described in detail and the functions combined and co-related, and illustrated by example.

The stylus board and depressor bar

As shown in the drawings (Figure 1), the machine comprises a casing or housing A, having on its upper surface a stylus board C in place of the conventional adding machine keyboard, with apertures D in place of the conventional adding machine keys. The stylus board as shown is arranged to accommodate a number having seven digits, although it will be obvious that the machine may be designed to handle any desired number of digits. Each digital representation comprises a vertically arranged row of apertures, nine in number, and between one or more of these rows, as desired, are arranged markings or indicia from 1 to 9 as at E, corresponding in numerical order with the aperture in lateral alignment or registration therewith. In Figure 1a, a modified form, the housing A' encases a keyboard mechanism with keys 110' substituted for the stylus openings.

Beneath each vertical row of openings D is a depressor bar 10 (Figures 5 and 6), which extends at least for the full length of the stylus board C. Thus, for a machine having seven rows or denominations of digits as shown, there are seven depressor bars as 10, 10a, 10b, 10c, 10d, 10e, and 10f. Each bar has an upper flat, table-like surface 11—11f, inclusive, which has a downwardly extending apron 12 having converging ends which terminate in a semi-circular bearing surface 13. This bearing surface is journaled over a pin 14 which projects from the face of a bell crank lever 15 which is pivoted at 16. The upper arm of this lever terminates in a dog 18 and the other arm is secured to one end of a spring 19 the free end of which is fastened to

40 a convenient point in the housing or frame. Each depressor bar 10—10f, inclusive, has associated therewith a selector bar or differential actuator 20—20f, respectively, each being provided with spaced longitudinal slots 21, 22, the bars riding on shafts 21a, 92, extending into these slots. Each selector bar or differential actuator has a rack 23 on its upper edge substantially midway of its length, and has a series of downwardly extending teeth 24 on its bottom edge substantially forward or to the left of said rack 23. A stop member 25 is shown pinned to the upper edge of said selector adjacent the forward end thereof. Obviously, this stop may be otherwise secured, or may be made integral with the bar. An angular bracket is also secured to or made integral with the bar below rack 23 and has a downwardly extending arm 26. A tension spring 27 is attached to this arm at one end to load the selector, for movement upon operation from the keyboard, the other end of the spring being suitably attached to the housing A or to the machine frame, as is well known in the art.

Each longitudinal row or column of keys together with the associated accumulator wheel or dial and the mechanism for actuating and controlling them may be referred to as denominations or denominations.

From the foregoing description, it will be seen that by inserting a stylus through an aperture,

for example, number 5 aperture in the units denomination as shown in Figure 6, and pressing lightly against the table 11, the pressure will cause the bearing surface 13 to engage pin 14, pivoting the bell crank lever about pin 16, causing the disengagement of dog 18 from teeth 24 of the selector. Under the tension of spring 21 the selector will shoot rearward until the stop 25 hits the stylus and stops the selector. Where used in this description, the word "forward" or "forwardly" will be interpreted to mean in a direction towards the front of the machine, or towards the operating bar F, and the word "rearward" or "rearwardly," towards the rear of the machine or towards the platen 91, as seen in Figure 3.

The accumulator wheels or dials are mounted on shaft 38 and are positioned above the selector bars over the racks 23. The rack 23 of each selector is normally disengaged from its corresponding dial or accumulator wheel 28', as shown in Figure 7, constituting an element of each ordinal accumulator assembly 28 including a unit having a gear of 10 teeth, an associated plate and pawl 28a and a dial having the usual indicia from 1 to 9 and 0 on its circumference. Thus, in an adding operation, the longitudinal movement of the selector and its rack will cause it to slide clear of the dial wheel until the stop 25 engages the stylus in the opening for the number selected. As the stylus is removed the table 11 moves up with it under the pull of spring 19 which rocks bell crank lever 15 about pivot 16 forcing the dog 18 back into engagement with the rack 24 which is now in an advanced position, the extent of this advance being governed by the number selected by the stylus.

If another such number as 6, for example, in the tens column or denomination is set up in the machine to be added to the foregoing unit 5, the foregoing operation is repeated, and to complete the addition the operating bar F is depressed. The bar F, as shown in Figures 2, 3 and 4, controls the arms 39, 39a, pivoted on shaft 37, and links 32, 33 and arm 34. The link 33 and arm 34 are fixed to the shaft 35, the arm 34 being duplicated as 34a on the other side of the machine, as shown in Figure 2. The arms 34, 34a and rod 36 form a bail and these parts will hereafter be referred to as bail 34'. Thus, it will be seen that the operation of bar F causes bail 34' to move to the left to carry out a sequence of operations which will hereinafter be described. To bring the dial mechanism into mesh with the selectors a camming plate 43 (Figures 3 and 4) is provided, which is pivoted on stud 43d projecting from the side frame of the machine (Figure 2). The plate 43 has an inwardly bent camming lip 43a adjacent the starting position of the rod 36 and another camming lip 43c at a position adjacent the extreme end of the stroke of said rod when it swings as a bail.

Carrying out the addition of the numbers heretofore set up in the machine to be added, as heretofore described, the bar F is depressed, causing the bail 34' to engage the camming plate 43 as it swings, the end of shaft 36, which projects slightly past arm 34, engaging cam lip 43a pulling plate 43 down and causing stud 43b thereon to engage and depress cam 42 on plate 39 (Figure 4). The stud 43b rides against the flat face of cam 42 camming it backwards and holding it there frictionally until the plate is bumped up as will hereinafter be shown.

The plate 39 is duplicated on the other side of the machine as 39a and the two are tied together by shaft 39 carrying the accumulator wheel assembly 28, this mechanism forming a carriage unit which is pivoted on shaft 37. The shaft 37, or pivoting point for the carriage, lies forwardly of the cam 42. Therefore, when cam 42 is engaged by the stud 43b the entire carriage is swung about shaft 37, bringing the dial or accumulator wheels 28 into engagement with the selector racks 23.

The continued forward movement of the bail brings rod 36 into contact with the arm 26 on the selectors, restoring them to their starting position, simultaneously rotating dial wheels 28 to set up therein and complete the addition of the two numbers we have selected. As the bail 34' approaches cam lip 43c the selectors reach a position where the last tooth of rack 24 is directly above dog 18 (Figures 3 or 4), which rides into position under the tension of spring 19. When the bail reaches cam lip 43c the projecting part of shaft 36 bumps the cam lip 43c, knocking plate 43 upwardly and disengaging stud 43b from the cam 42, permitting the carriage to return to starting position under the tension of spring 57.

Dial accumulators or registering and carrying mechanism

The dial registering mechanism comprises a series of accumulator wheel assemblies incorporating the dial or accumulator wheels 28' with associated plates and pawls 28a and a description of one assembly 28 will suffice for all as they are identical in construction and operation. These accumulator assemblies 28 are mounted on shaft 39 (Figure 7) which is carried by plates 39, 39a which are pivoted on shaft 37 supported by the side frames of the machine. The plates 39, 39a are fixed to the shaft 39 and, as heretofore described, form a carriage for the accumulator assembly and the carrying mechanism.

Each carrying unit includes a carrying plate 41, best shown in Figures 7, 8, 9, and each plate has its central portion cut away, encircling shaft 40. Formed integrally with the plate 41 and projecting into the central opening thus provided are two oppositely arranged, radially extending cam lugs 45-46 (Figure 7) which are also bent laterally in opposite directions as best shown in Figure 9. Positioned adjacent each camming plate on the square shaft 40 are resetting collars 48 and carrying plates 49 fixedly associated therewith on spacing hub 49a, each collar and plate forming a unit which is slidable laterally on shaft 40, the latter being carried by the carriage plates 39, 39a. These units will be referred to as carrying plates. The resetting collar 48 is of a diameter slightly less than the diameter of the central opening in plate 41, and it carries a short resetting stud or lateral projection 48a. The carriage is mounted for vertically swinging movement on shaft 37, which is supported by the side frames of the machine.

When a carryover is made in adding one digit to another, the dial or accumulator wheel, for example 28' in Figure 7, will rotate in a clockwise direction, with the pawl 28a rotating with it until it engages point 41a' of plate 41, camming it backwards against its pivot 37 lifting it slightly and thus bringing cam 46 into engagement with resetting collar 48 (Figure 8) of the carrying plate unit. The collar 48, with associated plate

49, being loosely supported on square shaft 40, will thus be pulled or shifted laterally into the central opening of plate 41 by said cam lug 46. The carrying plate 49 normally lies laterally of the adjacent dial wheel and has integral carrying fingers 52, 52a. Therefore, when cam 46 moves collar 48 laterally, fingers 52, 52a on plate 49 are also moved laterally directly into the path of the gear of the adjacent accumulator wheel representing the next higher digit. This is fully shown in Figures 7, 8 and 9.

After the carry has thus been set, it is necessary to complete, or add, the carry just set up. At this point the operating bar F is at the limit of its downward movement, having been depressed earlier in this description. Of course, the sequences heretofore described were performed almost instantaneously. With the operating bar F in this position, the accumulators in their mount on the carriage are in their elevated position, out of mesh with rack 23. At this time some means is needed to keep the dial wheels from spinning freely. For this purpose a shaft 53 is mounted on the side frames of the machine and on this shaft a hook-shaped detent 54 is pivoted, the detent having a nose 54a which engages the accumulator (a separate detent being provided for each accumulator) to keep it from rotating.

Another shaft 55 is supported by the side frames of the machine and is fixed in the path of the detents to limit their downward movement, as shown in Figures 7 and 9, when the carriage is dropped.

A tension spring 56, fixed at one end to a stud 54b on detent 54 and to bar 53 at its other end, tends to hold said detent in static engagement with the dial wheels when they are disengaged from the selector bar rack.

Another tension spring 57 is hooked at its upper end over the bar 55 and at its lower end over the shaft 38 on which the dials are mounted. This spring tends to keep the dials out of mesh with the selector bar racks 23 until the bar F is depressed to bring the cam plate 43 into play as heretofore described.

Restoring and resetting mechanism

I have brought the bar F to the limit of its downward travel and have brought bail 34' (Figure 3) to the limit of its forward travel. I must now restore the bail to its starting position which is done merely by releasing bar F.

Pivoted for swinging movement adjacent the side frame of the machine is a gear segment 58 (Figure 11) pivoted to the frame at 59 by means of an arm 60. The lower edge of the segment is toothed as at 58'. The arm 60 of the segment carries a short stud 60a. A bar 61 is fixed to shaft 35, the bar being positioned between arm 34 and the side frame of the machine and it is slotted at its upper end with the stud 60a projecting into this slot.

The shaft 38 carrying the dials or accumulators extends into the path of the gear segment 58 as shown in Figure 2. A spool gear having a hub 62 with gears 63 and 64 (Figures 2 and 11) mounted at opposite ends thereof is freely and rotatably mounted on shaft 38. The gear 64 is vertically aligned with the teeth on gear segment 58, and is meshed therewith when the dials and carrying mechanism are in elevated position.

When the bar F was depressed the arm 61, fixed on shaft 35 was actuated in the direction of the operator, transmitting its motion through stud 60a and arm 60 to gear segment 58 which is thus

rotated through an arc about its pivot 59. During this forward travel of the segment, when adding, it is not in mesh with gear 64 because the shaft 38 at this time is down, the accumulator

5 being in mesh with the selectors until released by plate 43. An angle plate 63a, arcuate in side elevation, as shown in Figure 4, is fixed to arm 60 at such a point below the segment 58 as to permit projecting end of shaft 38 to pass under said plate 63a, as shown in dotted lines in Figure 11, on the forward sweep of the segment, and to pass over the plate with the gear 64 in mesh with 58 on the return sweep of the segment, or vice versa, when subtracting. The arc of plate 15 63a is substantially concentric with that of the gear segment and the plate terminates short of the ends thereof so that the shaft 38 may slip over said ends and bring gear 64 into or out of mesh with the segment as the case may be. A 20 stud 65 projecting from the side frame of the machine holds gear 64 against rotation when it is out of mesh with segment 58.

The cam plate 43 pivoting around point 43d, normally will hold down the mechanism of the 25 accumulator carriage after the projecting stud of rod 36 has hit and passed over cam 43a. The plate 63a, however, will insure the retention of the mechanism in its depressed position by passing over the projecting end of shaft 38 on the 30 forward stroke of the bar 61 and bail 34' until the end of said stroke, when the projecting portion of rod 36, forming a stud (Figure 4) hits cam 43c and releases the carriage so that it may swing upwardly.

35 As the bar 61 and bail 34' return to their starting position, the gear segment, now in mesh with gear 64, causes this gear to rotate, transmitting its motion through hub 62 and gear 63 to gear 58, the ratio between the gear segment 58 and gear 50 being so proportioned that the latter is turned through one complete revolution, in adding, when the segment returns to its starting position. The gear 50 and its connected hub is mounted so as to be slidable laterally on square shaft 40, and also rotates with the shaft.

Addition cycle

The numerals 5 and 17 will be added to show a cycle of operation. The stylus is inserted at 5 in the units denomination and depressed, releasing selector bar 20 and arresting its movement five spaces to the right, as in Figures 3 and 4. Then bar F is operated, actuating the bail 34' and arm 61 with associated parts. As the bail and arm 61 move forward, the stub end of rod 36 first hits cam 43a forcing pin 43b against cam 42 rocking carriage 39 downwardly, putting the dial wheels into mesh with the selector bars. Continued movement of the bail causes rod 36 to engage arm 26 on the selector bar, pushing it back to its starting position, at the same time rotating the units order dial of the accumulator and setting up the number 5 in the dial. Near the end of its forward stroke the bail causes the stub end of rod 36 to hit cam 43c, raising it by swinging it on pivot 43d, thus causing disengagement of pin 43b from cam 42, spring 57 raising the dial carriage, thereby disengaging the accumulator dial from the restored selector bar.

70 Simultaneously with the forward movement of the bail, the arm 61, which is fixed on the same shaft 35, moves forward, carrying with it the gear segment 58 by means already described. As pointed out above, during this movement gear 64 is not in mesh with the segment, and shaft 38

rides under plate 63a. When the arm 61 reaches the forward limit of its travel, rod 36 hits cam 43c and shaft 38 is shifted upwardly; the relative positions of the segment 58 and gear 64 are then as shown in dotted lines in Figure 11, with the parts in mesh.

The bar F is now released, causing the bail and arm 61 to return to starting position. The return of segment 58 causes rotation of gear 64 (Figures 4 and 11), hub 62 (Figure 2), gear 63 and gear 50, the latter rotating one complete revolution. However, as no carry has been initiated from any lower order accumulator dial, the rotation at this time performs no function. I now have digit 5 registered in the units order dial and I am about to add the number 17.

The number 7 is set up in a manner similar to that of the number 5, as just described, the selector bar shooting to the right in Figure 4 seven notches or teeth. Then the numeral 1 is punched in the tens column and the corresponding selector moves to the right one notch or tooth. It is important to remember that during this movement of the selectors, when adding, the dials are not in mesh therewith. This is clearly shown in Figure 4.

Now the bar F is depressed so that the numeral 17 is added to 5. As the numeral 7 is added to the numeral 5 in the units dial, this dial is rotated a total of 12 steps and the finger 28a attached to this dial completes a revolution, clockwise, past point 41a' (Figure 7), raising plate 41 and causing cam 46 to engage resetting collar 48, drawing it laterally into the opening in plate 41 and pulling carrying plate 49 into the path of the gear of the tens dial so that tooth 52 (in addition) meshes with the gear of the tens dial, all as fully shown in Figure 9.

The bar F is now released, which causes bail and arm 61 to return again to starting position as outlined above, the gear 64 now meshing with segment 58. The return of the segment from its dotted line position as shown in Figure 11 rotates this gear and hub 62, gears 63 and 50. The gear 50 rotates one complete revolution thus rotating the shaft 40 and the members mounted thereon. The finger 52 of carrying plate 49, now in the path of the gear of the tens dial, rotates that dial by one tooth or step. As I have already set the number 1 up in this dial, this additional rotation of one tooth will register the number 2 in the tens dial. As the finger 52 clears the dial gear the continued rotation of shaft 40, on the half turn, brings pin 48a on resetting collar 48 into engagement with cam 46 on plate 41 forcing the plate downwardly, which causes cam 45, opposite cam 46, engaging the rim of collar 48, to push it or shift it laterally, or to the left as shown in Figure 8, moving the carrying plate 49 and finger 52 laterally out of the path of the dial gears and into neutral position. I now have a total of 22 registered in the accumulator dials, which is the sum of the 5 and 17 added.

The subtracting mechanism

In order to subtract with this machine, a subtract lever 66 (Figure 3) pivoted on stud 67 which is fixed to the frame, is pulled downwardly. This action causes cam surface 66a on lever 66 to engage dial shaft 38 and push it downwardly, bringing with it the entire dial mechanism and placing the dial gears into mesh with the selectors. The lever 66 has another arm formed as a hook 66b which engages a stud 68 on camming plate 43 and lifts it so that the bail 34 can pass with-

out engaging cam lip 43a, all as shown in Figure 3. A stud 69 is fixed on arm 34 so that when lever 66 is pulled downwardly the cam face 66c thereon is brought into the path of this stud.

- 5 The numeral 5 will now be subtracted from the 22 previously totalled to show a cycle of operation. The minuend 22 has already been registered in the dials. With subtract lever 66 set, the subtrahend 5 is then set up in the units dial 10 by selecting opening No. 5 in the stylus board and releasing the selector as previously described. When the selector moves rearward this time, in distinction to the action when adding, the dial gears are engaged on the rearward stroke of the selector because shaft 38 has been depressed by cam 66a. At this time the dial gears rotate in a counter-clockwise direction, and the units dial is turned back 5 steps or teeth turning the dial backwards from 2 to 7. By subtracting the 5 on 15 the units dial, the carrying pawl or finger 28a (Figure 8) strikes point 41a' lifting plate 41 and causing carrying plate 49 to be cammed over to the right as shown in Figure 8, as previously, described, bringing the finger 52a into the path of its associated dial gear in the tens column.

The bar F is now depressed, actuating the bail 34'. As the bail moves forward it performs the following several functions in this phase of its operation.

- 20 1. Resets lever 66: The stud 69 on bar 34 engages cam 66c of lever 66, resetting that lever to its starting position. The resetting of the lever causes 25 2. Rocking of dial carriage: The shaft 38 is caused to be released from contact with cam face 66a and the shaft is elevated by tension spring 57, (Figure 3) thus disengaging the dial gears from the racks of the selector bars, at the same time engaging gear 64 with segment 58.
- 30 3. Drops cam plate 43: The hook 66b on lever 66 is dropped, causing the cam plate 43 to drop.
- 35 4. Restores selector bars: The selector bars which were advanced are restored by bail 34' to their starting position where they are engaged by 40 45 5. Rotates gear segment 58: The rotation of gear segment 58 is caused by bar 61 associated with bail 34' and results in turning shaft 40 through gear 64, hub 62, gears 63 and 50 (Fig. 2), turning out the carry previously set up in the tens dial. In this action the finger 52a of the collar 48 associated with the tens column is rotated counterclockwise (Fig. 9) with the result that the corresponding dial is rotated back one tooth, setting up the digit 1 on the dial, and the pin 48a hits the cam lug 46 from the bottom, with the resulting lateral shift of the carrying plate and fingers, disengaging the latter from its dial gear.

- 50 60 The bar F is now released and we have the total 17 registered in the dials. Gear 64 remains engaged with segment 58 during the return stroke of the latter when bar F is released, but rotation of the shaft 40 by the gear is then idle.

Totalizing and clearing mechanism

To take a total and reset the dials to zero, a lever 70 is provided (Figure 4), suitably pivoted on a stud 71 carried by the side frames. At its lower end this lever is pivoted to a link bar 72 which has an upwardly extending arm 73 pivoted thereto at 72b and which is additionally pivoted to the side frame at 74. A similar arm 73a is provided on the other side of the machine (Figure 2 and these arms are joined by a crossbar

75 with which they form a bail and these parts will hereafter be described as bail 75'. This bail lies adjacent the overhanging stop portion 41a of the plates 41.

Intermediate the ends of link 72, levers 76, 76a are pivoted on opposite sides of the machine on a shaft 77 extending through the frame. A stud 72a is fixed to link 72 to the left of lever 76 as shown in Figure 4. The levers 76, 76a are joined by a crossbar 78, forming a bail and these parts will hereafter be referred to as bail 78.

By pulling lever 70 forward the link 72 is moved to the right as shown in Figure 4, causing pin 72d on projection 72c of lever 72 to hit the shoulder 66d of the subtract lever 66, thereby 15 swinging this lever about its pivot 67 and pulling the dial gears downwardly into mesh with the selectors as heretofore explained. Simultaneously with this movement, the bail 75' is swung forwardly or to the left (Figures 3 and 4) to seat under the projecting lugs 41a of plates 41. By the time the lever 66 has been shifted, and the bail 75' seated, the pin 72a on link 72 engages lever 76, forcing bail 78' against levers 76, 10 rocking them about their pivots 16 and withdrawing dogs 18 from the teeth 24 of the selector bars allowing them to be propelled rearward under the tension of springs 27. The dial gears, being in mesh with the selectors are thus rotated. The bail 75', having locked plates 41 against movement, prevents any carries from being set up. As we still have the number 17 registered in the dials, the units and tens dials will rotate counter-clockwise (Figs. 3 and 4) back to zero as the carrying pawls or fingers 28a, 28b abut against the points corresponding to 41a' on their respective plates 41. As these plates are locked against movement, the pawls or fingers stop, and the corresponding dials will be at zero. Those dials which were at zero when the selector bars were released will undergo no change.

Release of lever 70 restores bail 75' and dogs 18 to normal and removes pin 72d from contact with shoulder 66d. Operating bar F is then depressed to restore the selector bars, and to restore the subtraction lever 66 through engagement of stud 69 on arm 34 with cam face 66c on lever 66.

Correction mechanism

In order to make a correction on the machine where a digit has been erroneously punched in with the stylus or on the keyboard, a lever 79 (Figure 4) is provided which is pivoted to the side frames at 79a. One end of this lever, below pivot 79a, is pivoted to a link 80, the other end of which is slotted as at 80a and is supported by a pin 81 passing through said slot, the pin being supported at any convenient point in the side frame. Intermediate the ends of said link 80 two cams 80b and 80c are provided thereon. The cam 80c engages the latch 82 on the rearward movement of the link and lifts said latch. The other cam 80b engages lip 83a on lever arm 83 of a bell crank lever which is pivoted at point 67. The other arm 83b of this lever is designed to engage the pin 68 on cam plate 43 when the lever is actuated as will now be described.

Both cams 80b and 80c move simultaneously, shifting the indicated levers. The lifting of the latch 82 disengages the printing mechanism from the operating lever 34 to prevent printing, as will hereinafter be described. The lifting of the cam plate 43 by lever 83 is intended to raise cam lip 43a out of the path of bail rod 36 to prevent 70

the dial wheel mechanism from being pulled into engagement with the selector bars. With the cam plate 43 thus raised, all that is necessary to clear the error from the machine is to depress operating bar F, bringing operating bail 34' forward to engage the selector bars which were erroneously projected and restore them to their starting position. Lever 79 is then released.

Printing

The invention provides for two forms of printing mechanisms. In the form shown in Figure 3, a simple printing device is located at the rear of the machine, by means of which individual amounts and totals may be recorded on a tape as is well known in the art. The printing type 20a' is carried on the bottom face of the right hand end of the selectors 20 as best shown in Figure 3.

20 The forward movement of the arm 34 simultaneously engages latch 82 by means of pin 84 fixed on said arm and pulls the latch forward or to the left. A lever 85 is pivoted to latch 82 at 87 and this lever together with latch 82 is 25 pivoted to a portion of the machine frame at 86. A tension spring 88 acts to pull this lever to the right and keep the latch 82 in engagement with the stud 84, at the same time keeping shoulder 85b of lever 85 in engagement with lip 89 of plate 90. The lever 85 has a lip 85a at its lower end to support latch 82 and keep it from dropping when not engaged with stud 84.

When the bar F is depressed after a number has been set up in the selectors, the latch 82 will 30 be pulled forward or to the left, pivoting lever 85 about the pivot 86 so as to kick its shoulder 85b out of contact with lip 89. A rod 92 joins side plates 90, 90a (Figures 2 and 3) and passes through each of the selector bars as shown, the 35 plates being pivoted on shaft 37. A tension spring 93 is hooked at one end to the lip 89 and at its lower end is secured to any convenient point of the machine frame to snap the printing mechanism downwardly when the lever 85 is kicked from beneath lip 89. The forward movement of arm 34 not only causes the printing mechanism to drop, but also resets said mechanism. This is accomplished by means of a cam plate 94 pivoted to the frame at 95. The plate 90 has a downwardly projecting portion 90b which lies in the path of the plate 94. When the printing mechanism drops on the forward movement of arm 34, the point 90b engages the corner 94a of plate 94 and pivots said plate to the left. The plate has a cam surface 94b which is engaged by stud 69 on arm 34 as the latter moves to the left. As the stud passes under the cam on its initial movement the plate 94 is rocked on its pivot, swinging plate 90 and associated printing mechanism upwardly so that shoulder 85b becomes seated under lip 89, the spring 88 pulling it into seated position as the latch 82 is released from stud 84 by the camming action of its forward portion 82a against cam 80c of link 80 upon forward movement of arm 34.

Thus, in operation, after the selector bar or bars have been projected, the operation of bar F will kick out lever 85 and spring 88 will pull the bars down to print over the platen 91, which is secured to the frame of the machine in any convenient known manner.

When the bar F is released, the arm 34 moves back to its original position and latch 82 rides up and over the stud 84.

In the form of the invention shown in Figures

1a, 19 and 20, the printing mechanism is disposed at the front end of the machine, but since it is built into the repeat mechanism it will be described in conjunction therewith.

Stylus or keyboard check dials

These mechanisms are located adjacent the board checking device by means of which the operator can visually check the accuracy of the digits set up in the machine after each operation, and the machine is also provided with repeat addition or multiplication mechanism which requires only the repeat manipulation of the operating bar F, eliminating repeat stylus operations.

These mechanisms, are located adjacent the selector bars. The indicator comprises a series of dial, gear and cam units, one for each selector bar, as will hereinafter appear. As these dial, gear and cam units are identical in construction, operation and function, a description of one unit thereof will suffice for all.

A shaft 96 is mounted in the side frames of the machine above the selector bars, and the dials, gears and cams forming the units above referred to are mounted on said shaft. Thus, in Figure 3, we have a stepped, circular cam or stop member 97 fixed to the dial gear 98, to which is attached the dial 93a (Figure 2). The cam 97 has ten steps including the cypher, and the dial gears thereof are meshed with the selectors as shown.

Repeat addition or feedback mechanism

The repeat addition or multiplication and feedback mechanism is shown in Figures 3, 16 and 19. Figures 16 and 19 show modifications which may be substituted for the corresponding mechanism in Figure 3, and Figure 19 shows, in addition, a novel form of printing mechanism combined with the repeat and feedback mechanism. It will be obvious to those skilled in the art that if the printing mechanism of Figure 19 were used in Figure 3, the printing members shown in that figure would be omitted. In Figure 3, the repeat and feedback mechanism is located below the selectors as follows. Below the selectors a pair of tie-rods 99, 99a extend between the side frames of the machine, and the mechanism referred to is mounted on these rods. Each ordinal unit of said mechanism includes a vertically sliding latch or sensing lever 100 having upper and lower slots 100a, 100b through which rods 99, 99a, respectively, extend. This lever also has a forwardly directed extension 100c at one side carrying a stud 100d and at its opposite side the lever is toothed as at 100e for a portion of its length. At its upper end lever 100 has a sensing nose or pawl 100f. A tension spring 102 is joined at one end to rod 99 and at its other end to stud 100d on lever 100. Pivoted on the shaft 99 is an arm 101 having an extension 101a through which a bail rod 101b is passed, and having a pointed finger or pawl 101c extending in a reverse direction.

Pivoted at spaced points on shaft 31 (Figures 2 and 3) and joined by a connecting rod 103 to form a bail are a pair of cams 104a, 104a', one of which has an operating handle 104. The cam portion 104a extends along an axis substantially at right angles thereto and terminates in a cam face 104b having notches 104c and 104d at the upper and lower portions thereof, respectively.

Another lever 105 is pivoted to the machine frame on stud 100 (Figure 3) and this lever extends to the left of the pivot with an arm terminating in a lip 105a bent into the path of the

movement of the cam 104a. The other end of lever 105 extends to the right of its pivot with an arm terminating in a cam face 105b which abuts bail 78' heretofore described.

5 The operation of the indicator or keyboard check and repeat mechanism is as follows. We will assume that the unit 5 has been punched in the key (or stylus) board, releasing the selector and rotating the cam dial unit 97, 98, 98a, exposing the digit 5 in the units column of window G (Figure 1) and bringing the fifth step on cam 97 into alignment with pawl 100f.

A pull on lever 104 in the direction of the operator will cause rod 101b to ride out of notch 104c in cam plate 104a. As the cam passes upwardly over the rod, it pushes the latter laterally to the right and the lever 101, pivoting on rod 99 swings to the right disengaging pawl 101c from toothed rack 100e, whereupon tension spring 102 will cause 20 lever 100 to snap upwardly.

As the cam 97 has been rotated through an arc covering a span of five teeth, the pawl 100f of sensing lever 100 will engage the fifth step of said cam, as shown in Figure 6, to limit the subsequent

25 movement of the selector. As the rod 103 forms a bail with cam 104a and its complement 104a' on the other side of the machine, the mechanism for each selector corresponding to levers 100, 101 is similarly operated when the handle 104 is 30 pulled. Since, however, no number was punched in any of the other denominations, none of the remaining selector bars were actuated, so the remaining cams and dials corresponding to cams and dials 97, 98, respectively, were not rotated, 35 and the pawls 100f snapped into the zero step thereof.

While these sensing actions were taking place, the cam face 104b was riding over the rod 101b. When notch 104d moves into alignment with rod 40 101b, spring 102a, hooked at one end to shaft 31 and at the other end to rod 101b, pulls lever 101 forward, causing pawl 101c, to re-engage the toothed rack 100e at a lower point, thus locking sensing lever 100 at a fixed radial position with respect to the stepped cam and dial unit corresponding to the digit 5 setting thereof. The toothed rack 100e has teeth equal in number to the number of steps of the cam 97, that is to say, ten teeth or notches, so that if the fifth step on 50 cam 97 is engaged by pawl 100f, the fifth notch on rack 100e will be engaged by pawl 101c.

As the rod 101b drops into the lower notch 104d, the top edge of cam 104a, moving upwardly, engages lip 105a of lever 105, causing it to pivot 55 around point 106, pushing cam face 105b against bail 78' which in turn rocks the lever 17 of each selector bar mechanism, disengaging dogs 18 from said bars. The spring 27 will tend to pull the bars to the right as seen in Figure 3, and the bail 34' will restore them on operation of bar F.

At this point we have the unit 5 set up in the machine and the repeat mechanism set accordingly. If we wish to repeat this numeral, all that remains to be done according to this invention is 65 to depress the operating bar F as many times as it is desired to repeat the number. Depressing bar F first brings the dial carriage down, bringing the dials into mesh with the selectors, and as the bail 34' continues to go forward it returns or restores the units order selector to its starting position, thereby rotating the dial. As bar F is released, the dials swing out of mesh with the 70 selectors, bringing the gear 64 into mesh with segment 52 actuating square shaft 40 one revolution, to enter any carries set up in the machine.

Such release also accomplishes the additional function of allowing the selectors to return to indexed position. Pushing and releasing bar F again repeats the cycle. In order to normalize the machine following a repeat operation, it is only necessary to return lever 104 rearwardly to its normal or home position while bar F is held depressed for the last repeat cycle, so that the selectors will not return again to indexed position when the bar F is released.

The repeat mechanism will not only repeat what has been set up in the selectors through the keyboard, but will also pick up and repeat accumulated totals without, as in other machines, manually setting up again on the keyboard the total it is desired to pick up. In other words, the total is fed back to and sets the selector, and the repeat mechanism merely senses and retains that setting. The following illustration will exemplify this feature: We will assume that we have a total of 22 carried on the dials, and we now wish to multiply this by 5. The totalling or clearing lever 78 is pulled which clears the accumulator dials but, as heretofore explained, will reflect the number 22 through the selectors to the keyboard indicator dials 98a. Then lever 101 is pulled which causes fingers 109 to sense the dial cams and be differentially positioned in accordance with the position of the selectors, that is, they engage, respectively, the second step of the cam of the units and tens selectors as only these are in an advanced position. Now the bar F is operated to restore the machine to starting position. The accumulator dials now being cleared, it is necessary only to operate bar F five times to carry out the desired multiplication with the product appearing in the accumulator dials. If it is desired to clear the machine, this may be done by pulling the clearing lever 79 and then operating bar F as described. The setting of the selectors, or the digits set up therein, can always be determined by a glance at the indicator dials 98a through the window G.

Thus, for example, if a workman's time was being calculated, and the number of hours had been totalled, it would ordinarily, without this mechanism, be necessary to copy back to the keyboard by manual means the total number of hours worked so that it could be multiplied by the rate per hour to determine the amount due the workman. With this repeat or feedback mechanism the said total is automatically fed back into the repeat mechanism by first pulling totalling lever 78 which releases the selectors which project rearward to clear the accumulator dials as heretofore described. With the selector bars thus advanced, the lever 104 is then pulled, which actuates sensing lever 100 as explained, into engagement with said selector bar dial cams 97 to take up the total cleared from the accumulator dials. We would then have the total number of hours transferred back to the repeat and feedback mechanism, and by manipulating the operating bar F this amount could be multiplied by any single digit multiplier, such as the rate per hour, to determine the total pay due the workman. In the same way discounts and other computations could be calculated.

After the repeat mechanism has performed its function it is restored to its starting or rest position by pushing lever 104 in a direction away from the operator, or to the right as shown in Figure 3. This causes crossbar 103, which is carried by cams 104a, 104a', to engage the forwardly directed projection 100c of lever 100 and pull same down-

wardly, the cam face 104b simultaneously disengaging dog 101c from toothed rack 1004. Error lever 79 and operating bar F are then operated to restore the selectors. The mechanism is shown in starting or rest position in Figure 3.

Another form of repeating and feedback mechanism is shown in Figures 16-20, inclusive, and in this form of the invention a novel printing mechanism is associated therewith. Also, in this 10 form of the invention, the repeating and feedback mechanism, together with the printer may be shifted at will from a lower to a higher denominational order and vice versa to perform a variety 15 of computing and recording functions. This form of the invention is adaptable for the preparation 20 of various business records such as are customarily kept on cards, and with the innovations 25 about to be described an operator may optionally print one or more columns of figures thereon without the necessity of shifting the card or form. Such columns may be identical where duplicate work is necessary, or either column may be an accumulative total, or each column may represent separate or individual totals, or they may 30 represent a combination of separate and accumulative totals.

Associated with each selector is a keyboard 35 mechanism as shown in Figures 16, 17. Each key has a button 118 and a downwardly extending stem 125 surrounded by a compression spring 126. Pivoted to each key at 127 is a downwardly extending latch member 128 which passes through 40 the stem opening in keyboard plate 108 and terminates in a narrower or reduced extension 128' having a hook 128a adjacent the depressor bar 122. The spring 126 is supported between the horizontal arm 128b of latch member 128 and sub-frame plate 103. The latch member, where it passes through plate 108, has a cam edge 129 45 which engages with the wall of the opening in plate 103 as will hereinafter be described.

In this form of the invention, a sliding lever or 50 latch 100' having a bent lip 100a' is mounted to slide vertically on bars 99, 99a to engage the stop 97''' of selector bar 20' which is also modified. The latch 100' also has a lateral extension 100c' at one end and at its opposite edge is toothed as a rack 100e' for a portion of its length. A tension spring 100a' is joined at one end to rod 99 55 and its other end to stud 121' on latch 121. The arm 101' in the form of a bail (Figure 18) is pivoted on rod 99 and has a downwardly extending skirt portion terminating in a knife edge 101c projecting laterally in the direction of the toothed rack 100e'. The skirt portion is bent around the sides as shown in Figure 16 and forms a cam surface 101d' corresponding in function to cam notch 104d of Figure 3. Latch 121 is pivoted to latch 100' at 121a, the latch being offset 60 to the left at its pivot and extending downwardly therefrom to form a support for stud 121'. The upper end of the latch has a cut-away notch 121' which engages the terminal lip 100a of arm 120.

As already indicated, the selector 20' is modified in this form of the invention, the bottom edge thereof being provided with an elongated cam face 97'', corresponding in function to cams 97 (Figure 3). A notch or cut-away 97''' is formed adjacent the inner end of the cam. The arm 120 of the depressor bar 122' has an angularly bent lip 120a which extends into notch 121' of arm 121.

A lever 104' is pivoted on shaft 77' and has a lateral extension 104a' which carries rod or bail 75

101b', which is supported in a manner similar to rod 101b, as shown in Figure 2.

In the operation of this mechanism, depressing any key causes latch 128 to pivot on 127 as cam 129 rides over the edge of the aperture in plate 108, forcing hook 128a beneath the depressor bar 12''. The casing A' limits the downward stroke of the key. The bar 12'' at its right hand end, looking at Figures 16 and 19, pivots on rod 130 and is supported at its left hand end by a light tension spring 131 dropped from the casing of the machine.

Depressing a key 110' slightly will cause the stem 125 to press against depressor bar 12'', lowering it and its connected arm 120. This causes member 121 to push against its pivot 121a and exert downward pressure against connected sensing lever or latch 100', thereby disengaging it from stop 97'', and releasing the selector for movement under the tension of spring 27'. This causes selector cam 91'' to snap against lip 100f' of the sensing lever or latch 100', forcing the said lever downwardly, thereby likewise carrying downwardly the depressor bar 12'' through its connected arm 120, the movement now being continued by the pull of spring 27'. This downward movement continues sharply until the lower edge of depressor bar 12'' strikes the lug 128a of the key depressed and snaps the key to the limit of its stroke against the casing A'. The spring 27' is more powerful than spring 131 at the left end of the depressor bar and easily overpowers the latter. Thus, it will be seen that the touch of the key 110' merely starts the action which releases the selector, the force of the selector spring pulling the cam 91'' over the sensing lever 100', forcing said lever down, snapping the depressor bar down and pulling the key with it for the completion of its stroke. The distance between the lower edge of the depressor bar 12'' and the lug 128a of the key varies with the value of the key, so that when the depressor bar is arrested in its downward movement, it also arrests the lever 100' in a corresponding position on the cam 97''.

Actuation of the number one key (to the left in Figure 16) will cause the bar 12'' to move downwardly a short distance during which movement surface 129a engages lug 128a, unlatching selector 20' as heretofore described, and at the same time releasing latch 100' causing the selector to move forward unit distance until the cam 97'' thereof engages lip 100f' at a point adjacent the high point of the cam 97'' and to register the numeral 1 in the corresponding accumulator dial. Similarly, actuation of the number 9 key (to the right in Figure 16) would displace latch 100' nine times the distance it was depressed by the number one key, carrying lip 100f' with it, so that when the selector 20' moves forward the cam surface 97'' will be stopped by lip 100f' at the lower point of the cam, registering the number 9 in the corresponding accumulator dial. The space on cam 97'' is calibrated equally between these points corresponding to the number of keys to control the respective positions where the cam 97'' engages lip 100f' when any of the remaining corresponding keys are depressed. In other words, each key from 1 to 9 establishes a different or stepped relationship between the cam surface 97'' and lip 100f'.

If it is desired to repeat any number indicated by the key operated, the lever 104' is pulled in the direction of the operator, pivoting bail 101b' about its pivotal axis 77' and causing the cam notch 104d' to be pulled into the bail by spring

102a', thereby permitting the edge 101c' to engage in the tooth of rack 100e' which faces it, locking latch nose 100f' at its arrested point on cam 97''. As the edge 101c' moves in the direction of the rack 100e' it engages the lower arm 121b of latch 121, pivoting the latch around pivot 121a, thereby disengaging notch 121'' from lip 120a, releasing the depressor bar for return to its normal position by tension spring 131. It

will be understood, of course, that when latches 121 and 100' moved downwardly, as described above, the rack 100e' was depressed a distance equal to the number of teeth represented by the key depressed bringing, for example, tooth No. 5 into position opposite pawl edge 101c' if the key having the digit 5 was operated. At this time, if it is desired to repeat, or multiply this number, it may be done by repeat operation of operating bar F as described in connection with Figure 3.

To restore the mechanism to its starting position the bar F should be depressed so that bail 34 may return the selector bars. The bar F is held down momentarily, during the last repeat cycle, while lever 104' is pushed away from the operator or to the right as seen in Figure 16, so that bail 101b' may ride out of notch 104d' and upwardly along the cam surface thereof withdrawing knife edge 101c' from rack 100e' thereby permitting the sensing lever and latch assembly 100', 121 to snap upwardly under the tension of spring 100a'. At this time the notch 121'' of lever 121 will snap over lip 120a of arm 120 to lock the sensing lever and latch assembly to the depressor bar.

It will be noted that in this modification, Figure 16, the indicator dials 98' are interposed between the selector bar rack and dial gear 28'. The interposition of this gear, of course, reverses the direction of rotation of the accumulator dial gears 28' so that they rotate clockwise to subtract and counter-clockwise to add instead of the reverse, as explained in connection with Figures 3-12, inclusive. Therefore, with this modification, it is necessary to reverse the direction of rotation of shaft 40 of the carrying mechanism, which may be done in any well known manner.

In Figure 19, the mechanism shown in Figure 16 is combined with a novel form of printer for printing amounts or totals. In this form of the repeat mechanism each latch 100''' has a forward extension 132 along its forward edge with a gear rack 133 cut into the free edge of the extension. A shaft 134 is fixed to the sub-side frames of the machine as shown in Figure 20, and printing segments 135 are pivoted thereon for swinging movement. Each printing segment has teeth 135a which mesh with teeth 133 and carries printing type 29a' on its lower edge. It will be obvious that vertical movement of latch 100''' will rotate the printing segment so as to present the type of any number, corresponding to the key operated, on or over the printing platen 91'. The platen 91' is supported by a pair of oppositely disposed angle irons 136, only one of which is shown in Figure 19, which pivot on shaft 77'. A small plate 94' is fixed to the vertical side of the angle iron 136 and is provided with a cam surface 94b'.

This printing mechanism is controlled by the actuation of operating bar F' and extension thereof 30' pivoting around 31a. A dog 85' is pivoted to the sub-side frame at 85'' and normally locks into engagement with pin 137 projecting from the side of angle iron 136. A link

32' connected to extension 30' has a pin 69' projecting from the side thereof into the path of cam 94b'. A small angle plate 138 having a bent lip 82' is pivoted at 139 to the inner side of link 32' in such a position that it engages the dog 85'. At its forward end the plate 138 has an upwardly extending lug 138a to which a spring 140 is secured, the other end of the spring being fastened to link 32'. A small pin 141 is fixed in the link 32' to prevent the plate 138 from swinging over on its pivot in a forward direction.

To operate the printing mechanism, the operating bar F' is partially depressed, moving link 32' rearward, or to the right as seen in Figure 19, immediately causing lip 82' to unseat dog 85' allowing platen 91' to snap upwardly against type 20a' under the pull of tension spring 93'. Continued downward movement of operating bar F' causes pin 69' to ride up over cam 94b', thus forcing the platen 91' to return to its starting position. As the platen and its supporting arms 136 move downwardly, spring 88' reseats dog 85' over its pin 137, locking the platen in its lower position. When operating bar F' is released and link 32' moves forward, or to the left as seen in Figure 19, the lip 82' of plate 138 will engage the bevelled end edge of dog 85' and will slip under it, pivoting on point 139 under the tension of spring 140, and the lip will resume its starting position under the dog 85'.

An advantageous feature of the printing mechanism shown in detail in Figure 19 is that once the desired keys have been depressed and the selectors advanced to the point where they are cammed against lip 100f', the operating bar F' is relieved of the weight and drag of the printing segment 135. If, for example, any key 5 were depressed the corresponding selector would be projected rearwardly until cam face 97'' was stopped by lip 100f'. The downward movement of latch 100''' rocks printing segment 135 about its pivot to present the type number 5 over the printing platen. With the lever 104' set to lock knife edge 101c' into rack 100e' the segment would then be held in that position during all repeat operations, thus lightening the load on the operating bar F', and speeding up its operation. This construction also eliminates the possibility of error occurring through an overthrow or under throw of the printing means which might result from fast, repeat movement of the operating bar.

Another feature of the feedback and shifting mechanism in association with the check dials 98', as shown in Figures 1a and 16, is that any value carried in the repeat mechanism is always reflected in the check dials 98', whether carried in the accumulator or not. As the dial 98' is always in mesh with the rack of the selectors (Figure 16) any total carried in the feedback mechanism will always be reflected in these check dials. One advantage of this occurs when a stylus keyboard is used, so that it is easier to read what has been recorded in the machine. Even with a conventional keyboard, the check dial affords a convenient manner of reading at a glance what has been recorded in the machine.

The number shown in the check dials may be shifted from one side of the machine to the other in a manner similar to the shifting accomplished as hereinafter described in connection with this feedback mechanism.

In order to feed any amount carried in the accumulator back to the repeat mechanism shown in Figure 16, the total lever 70 (Figure 1a) is

pulled in the direction of the operator. Link 72', Figure 16, functions in the same manner as link 72, Figure 4. On actuation of the totalling lever (not shown in Figure 16) link 72' moves to the right as shown in Figure 16 until stud 72a' engages arm 76'' of arm 76' which forms part of a bail 78'. Bail 78' (Figures 16 and 19), rests on shoulder 100c' of lever 100' (Figure 16) and is forced downwardly by this movement, pulling latch 100' (Figure 16) or 100''' (Figure 19) with it, releasing the selectors. It will be obvious from the construction that lever 66 will be actuated by stud 72d, pulling the dials into mesh with the selector racks before stud 72a' engages 76 (Figure 4) or stud 72a' engages 76'' (Figure 16). This rocks the accumulator dials into mesh with the selectors and releases them from lip 100f' for rearward movement, clearing the accumulator dials, at the same time picking up the amounts carried in said accumulator dials and camming said amounts into latches 100' (Fig. 16) or 100''' (Fig. 19) of the repeat mechanism. Pulling lever 104' toward the operator locks these amounts in the repeat mechanism so that they may be repeated if desired, and in the manner heretofore outlined. They may be repeated in the same denominative column or may be shifted to another denomination, according to the need of the situation, as outlined in the shifting mechanism about to be described.

Shifting mechanism

When the machine is used for calculating, a mechanism for shifting the dial accumulators is provided as shown in Figures 12, 13 and 14. A pair of shafts 37, 37' are fixed in the side frames of the machine and extends across the same. A pair of oppositely disposed plates 112, 112' are mounted for lateral sliding movement on shafts 37, 37', these plates being tied together by rods 53, 55, and 38, thereby forming a carriage. The rod 38 carries collars 38a fixed thereto on the inside of the plates 112, 112' so that the rod will shift with the carriage. This carriage supports the dial assemblies 28 and the pawls 54 which lock them against involuntary rotation. A shifting handle 113 is fixed to plate 112 of the carriage in any convenient manner and is spring pressed and arranged to cooperate with a perforated and slotted plate 114, whereby shifting may be accomplished by depressing the handle 113 and sliding it along said plate 114 as many spaces as it is desired to have digits or decimal spaces in the result sought. Calculating or multiplication may then be accomplished through the keyboard or stylus board as heretofore described, the manner being well known in the art.

Instead of having the shifting mechanism adjacent the dials, as shown in Figure 12, it may be positioned at the front end of the machine, below the keyboard as shown in Figure 20. In this view the sub-side frames 39, 39a are fixed to the base of the machine and are otherwise supported by tie rods 99, 99a and shaft 134. Between these fixed sub-side frames and slidably on the tie rods 65 a pair of spaced sub-side frames 112'', 112''' are mounted, these frames being fixed to shaft 134 by means of collars 142 fixed to said frames and having appropriate set screws or pins to secure them to the shaft so that they may be shifted therewith in a unit as a carriage. The several printing segments 135 are pivoted on shaft 134 (only one being shown) suitably spaced from each other by any appropriate means, each engaged with a corresponding latch assembly and selector bar as shown. An arm 112a' carrying the shifting but-

ton 113 is fixed to the outer face of the left-hand movable sub-side frame member 112".

Before making a shift, the operating bar F' must be depressed and held down to keep bail 34 against the selector bars as shown in Figure 16. Otherwise, as lip 100f' is shifted to the left the selector bars would slide forward without any means to hold them.

In shifting for multiplication, division, or to establish any number of required decimal places, the button 113 is depressed. As the arm 112a' to which this button is attached, is secured to the shifting carriage, by depressing the button and moving it to the left as seen in Figure 1a, the carriage comprising plates 112', 112'', with the printing segments 135 and latch assemblies therebetween, may be shifted as many spaces as the capacity of the machine will permit. In dividing with this machine lever 66 would have to be depressed or pushed downwardly at every cycle to set the machine for subtraction, as previously explained, before the depressed bar F' is released. When this is done, stud 69 in returning to the Fig. 3 position after release of bar F' displaces lever 66 counterclockwise slightly to ride under cam lip 66c, this displacement being accommodated by the form of the cam notch at 66a in lever 66 without releasing shaft 38.

When the shift is completed, the operating bar may be released. As a substitute for the lip 100f' when it is shifted, an arm 101f'' (Fig. 20) which is fixed to the movable plate 112'' moves with latches 100' when it is shifted and arm 101f'' slips into the notch 97''' to hold the selector or selectors as required when bar F' is released. When there are less printing segments 135 or latch mechanisms 101' (Fig. 16) than there are selectors, the plate 112'' (Fig. 20) would carry an arm similar to arm 101f'', but extending in the opposite direction, to hold the leftmost or outbound selectors. It is understood in the art that as many additional selectors are placed to the left of the keyboard as it is desired to have decimal spaces or whole numbers. Thus, as shown in Figure 1a, for example, five additional selectors are provided to the left of the keyboard so that we may shift five spaces or digits to the left.

Keyboard mechanism

A keyboard may be substituted for the stylus board without substantial changes in the machine. As shown in Figure 15, a selector 20', having a stepped cam 97' is substituted for the selector 20, and an arm 12' pivoted at 12a is substituted for the depressor bar 12. A keyboard having upper and lower plates 107, 108' is supported by cross-bars 109, 109a extending from the side frames of the machine. Keys 110 are supported by these plates with their shanks 110a extending therethrough. Compression springs 111 are connected to their shanks and the mechanism is so constructed and arranged as to return the keys to starting position after being depressed, as is well known in the art. When lever 100iv is substituted for sliding lever 100, Figure 3, the only difference between the two is that the lever 100iv has a square rather than a pointed end to engage the steps of cam 97', and the stud 101b will rest on cam face 103b instead of in notch 104c; thus disengaging dog 104c from rack 100c. The dog is maintained in disengaged position in this form of the invention because the lever 100iv is in constant engagement with the cam 97' (Figure 15) whereas in Figure 3 it is not. In Figure 15, the dog 17 is eliminated. When a key is depressed the

downwardly extending arm of the bar 12' drops 100iv a distance equal to the depth of steps on the cam required to stop the selector according to the key depressed. The spring 27 (not shown in Figure 15) pulls the selector to the right as soon as 100iv is released from the first step of the cam. The remaining mechanism for controlling lever 100iv is identical with that shown in Figure 3 which has already been described.

In the operation of the keyboard, actuation of a key will cause it to strike depressor bar 12', which will swing on pivot 12a, causing its free end which is L-shaped in side elevation, to strike stud 100' sliding the lever downwardly a distance sufficient to release the selector bar so that it can snap to the right a number of steps indicated by the digit on the key depressed. It will be noted that the keyboard mechanism is so constructed and arranged that the actuation of a key will release the corresponding selector for re-engagement with lever 100iv at a step on the cam 97' corresponding to the digit on the key depressed.

In this modification, the dial indicator mechanism 98' for the keyboard is mounted on shaft 12a but it functions in the same manner as indicated with respect to Figure 3.

Where used in the specification the words "keyboard" and "stylus board" and "key" and "stylus" will be considered synonymous unless the context indicates otherwise.

While the foregoing drawings and description illustrate and describe preferred embodiments and modifications of the invention, these are not to be construed as limited to the construction shown, but the invention is to be given an interpretation commensurate with the scope of the appended claims.

I claim as my invention:

1. In a computing machine or the like, in combination, a keyboard, a denominational series of spring impelled selectors controlled thereby, means for locking said selectors in normal position, each selector being released from said locking means for movement from normal position upon actuation of a key of corresponding denominational order, means for restoring said selectors to normal position including an operating bar, a stop member connected to each selector and synchronous in movement therewith, each stop member being contoured to control stopping positions for said selector of the order of from one to nine to correspond to the keys of the keyboard, a differentially adjustable latch means for each selector for engaging said stop member on the movement of the selector to limit the stroke thereof in accordance with the key operated, key actuated means for releasing said locking means, said key actuated means controlling the movement of said latch means to a differentially adjusted position, a printing segment pivoted adjacent each said latch means and connected thereto for concurrent adjustment when the latch means is differentially adjusted, a platen yieldingly mounted for swinging movement beneath said segments, and means operable by said operating bar for swinging said platen against the printing segments upon actuation of said operating bar.

2. In combination in a computing machine or the like, a keyboard, a denominational series of spring impelled selectors releasable for movement from normal position under spring tension by operation of the respective keys of said keyboard, each selector having a stop member thereon graduated in steps corresponding to the number of keys in the respective keyboard order, spring

means urging said selectors from normal position, latch means releasably holding said selectors in normal position, adjustable intercepting means operable by and cooperable with said stop members to arrest the corresponding selectors in differential position corresponding to the depressed keys, means actuated by an operated key for releasing said latch means and regulating the adjustment of said intercepting means, accumulator dials engageable with and operable by said selectors, means for restoring said selectors to normal position, means for clearing said dials including means for releasing said latch means and for arresting said dials in zero position whereby said selectors are differentially positioned and said intercepting means adjusted according to the total cleared, manual means to releasably latch said intercepting means in adjusted position corresponding to the total cleared, and means for shifting said intercepting means from one denominational series of selectors to another for a computing operation.

3. In a computing machine, the combination comprising a keyboard having ordinal banks of keys, an accumulator, ordinal spring-loaded key-started selectors operable by the keys of said keyboard to actuate said accumulator, manually operable means for restoring said selectors to normal position, each selector having a zero stop portion thereon and a graduated cam surface adjacent said stop, ordinal latch mechanism releasably engaging said stop to hold the selector in normal position against the spring tension thereof and operable by a depressed key of corresponding order to release said stop and engage said cam, means connecting said latch mechanism to the respective banks of keys of said keyboard, said connecting means comprising a depressor bar connected to said latch mechanism and underlying the stems of said keys, key latches having means for engaging the lower edge of the depressor bar at graduated distances therefrom pivoted on said keys and movable to engage said bar when a key is depressed, and stop means for limiting the depression of the keys, whereby partial depression of a key will displace said latch mechanism to release said stop and position said latch mechanism for engagement and further displacement by said cam so that advance of the selector will force the operated key to the completion of its stroke and its advance differentially limited accordingly, means for releasably locking said latching mechanism in displaced position, and manually operable means for rendering said locking means effective.

4. In a computing machine, the combination defined in claim 3 and further characterized in that said latch mechanism incorporates a rack, said means for releasably locking said latching mechanism comprises a shiftable bail selectively engageable with the teeth of said rack, and said means for rendering said locking means effective is connected for shifting said bail selectively to engage or disengage said rack teeth.

5. In a computing machine, the combination defined in claim 3 and further including means operated by said locking means for disengaging said latch mechanism from said depressor bars, whereupon repeat operation of said selector restoring means serves to repeat the value of a depressed key in said accumulator.

6. In a computing machine, the combination defined in claim 3 and further characterized in

that said latch mechanisms are shiftable to adjacent orders.

7. In a computing machine having an accumulator, the combination comprising a keyboard, a spring loaded, key started, selector operable from said keyboard to actuate said accumulator, a stop on said selector, spring means urging said selector from normal position, a latch mechanism for engaging said stop to hold said selector in normal position against the tension of said spring means, a cam on said selector adjacent said stop; a depressor bar operable by the keys of said keyboard pivoted adjacent said selector and connected to said latch mechanism; a stop for limiting the movement of said keys, the stems of said keys resting on said bar; a key latch pivoted on each said key and swingable into the path of said bar when the key is depressed, the free end of said key latch having means for engaging the lower edge of said depressor bar, the distance from the lower edge of said bar to the engaging means varying according to the value of the key; said parts being so constructed and arranged that slight depression of a key will actuate said depressor bar to release said latch mechanism from engagement with said selector stop, thereby releasing said selector for movement under the tension of said spring means, said cam thereupon engaging said latch mechanism and depressing same, thereby further depressing said depressor bar and into engagement with said key latch-engaging means pulling said key to the limit of its downward stroke under the pull of said selector spring means, and thereupon stopping said latch mechanism on said cam, said selector thus forcing said key to the completion of its stroke after manual starting; an operating bar for restoring said selector after release, a printing segment pivoted adjacent said latch mechanism, said segment being operably connected to said latch mechanism so as to swing about its pivot when the latch mechanism is actuated; and a printing platen pivotally supported for swinging movement with respect to said segment, means yieldably urging said platen against said segment, means locking said platen against swinging movement towards said segment, said means including a tripping member, means connected to said operating bar to trip said tripping member when the operating bar is moved to restore said selector, said tripping movement releasing the platen for a printing operation.

8. In a computing machine, the combination comprising a keyboard having ordinal banks of keys, an accumulator, ordinal selectors differentially operable by the keys of said keyboard to actuate said accumulator, each selector having a zero stop portion thereon and a graduated cam surface adjacent said stop portion, spring means tensioning said selectors from a normal position, ordinal latch mechanisms releasably engaging said stop portions to hold the selectors in normal position against the tension of said spring means and operable by a depressed key of corresponding order to release said stop portions and engage said graduated cam surfaces, ordinal depressor bars connected to said latch mechanisms and each actuated initially by a depressed key of corresponding order to operate said latch mechanisms for releasing said selector stop portions, stop means for limiting the depression of said keys, key latches carried by said keys for engaging said depressor bars at graduated distances and differentially limiting further depression of said keys.

sion of said bars upon depression of said keys to the limit determined by said stop means, whereby a released selector forces the depressed key to the limit determined by said stop means through engagement of said graduated cam surface with said latch mechanism and the released selector is thereby arrested differentially in correspondence with the value of the depressed key, and means for restoring said selectors to said normal position and said latch mechanisms to holding engagement with the stop portions thereof.

9. In a computing machine, the combination defined in claim 8 and further including a sub frame positioned below said selectors, all of said latch mechanisms being mounted on said sub frame, said sub frame being laterally shiftable ordinarily relative to said selectors, the respective latch mechanisms moving into operating relation with respect to the selector of the next adjacent orders upon shifting of said sub frame, and a fixed arm carried by said sub frame adjacent said latch mechanisms and movable therewith into engagement with the outboard selectors.
